DESIGN FOR AN APRON

Andrew L. Henkel, Chicago, Ill.

Application April 23, 1943, Serial No. 110,023

Term of patent 3½ years

To all whom it may concern:

Be it known that I, Andrew L. Henkel, a citizen of the United States, residing at Chicago, Cook County, Illinois, have invented a new, original, and ornamental Design for an Apron, of which the following is a specification, reference being had to the accompanying drawing, forming a part thereof.

Fig. 1 is a front perspective view of an apron showing my new design;

Fig. 2 is a rear perspective view thereof;
Fig. 3 is a sectional view thereof on the line 3—3 as indicated in Fig. 1; and
Fig. 4 is a sectional view thereof on the line 4—4 as indicated in Fig. 1.

I claim:

The ornamental design for an apron, substantially as shown.

ANDREW L. HENKEL.
